UNITED STATES PATENT OFFICE

120,628

DESIGN FOR A COMBINED HOLDER AND BRACKET FOR A CONTAINER OR THE LIKE

William J. Jembrzycki, Chicago, Ill.

Application March 16, 1940, Serial No. 90,985

Term of patent 7 years

To all whom it may concern:

Be it known that I, William J. Jembrzycki, a citizen of the United States, residing in the city of Chicago, in the county of Cook and State of Illinois, have invented a new, original, and ornamental Design for a Combined Holder and Bracket, for a Container or the like, of which the following is the specification, reference being had to the accompanying drawing, forming part thereof.

In the drawing:

Fig. 1 is a perspective view of a combined holder and bracket, for a container or the like, showing my new design; and

Fig. 2 is a side elevational view thereof.

I claim:

The ornamental design for a combined holder and bracket for a container or the like, substantially as shown.

WILLIAM J. JEMBRZYCKI.
